UNITED STATES PATENT OFFICE.

NOBLE C. DOSS, OF ROME, GEORGIA.

SELF-HEALING INNER TUBE.

1,234,144.

Specification of Letters Patent. Patented July 24, 1917.

Application filed August 2, 1915. Serial No. 43,284.

To all whom it may concern:

Be it known that I, NOBLE C. DOSS, a citizen of the United States, residing at Rome, in the county of Floyd and State of Georgia, have invented certain new and useful Improvements in Self-Healing Inner Tubes, of which the following is a specification.

My invention relates to a compression or self-healing inner tube for a double tube tire. 10 An important object of the invention is to provide an inner tube of the above mentioned character, which is expandable in all directions, so that when it is placed in a non-extensible outer casing or shoe and subjected to 15 pressure, all portions of the inner tube are placed under compression, whereby a puncture or the like occurring in the inner tube will be instantaneously closed or sealed.

20 Another object of the invention is to provide an inner tube of the above mentioned character, which is simple in construction, inexpensive to manufacture, strong, and durable.

25 Other objects and advantages of the invention will be apparent during the course of the following description.

30 In the accompanying drawings, forming a part of this specification and in which like numerals are employed to designate like parts throughout the same.

Figure 1 is a side elevation of an inner tube embodying my invention,

Fig. 2 is a plan view of the same,

35 Fig. 3 is a transverse sectional view taken on line 3—3 of Fig. 1,

Fig. 4 is a similar view taken on line 4—4 of Fig. 1,

40 Fig. 5 is a longitudinal sectional view taken on line 5—5 of Fig. 2, and,

Fig. 6 is a similar view taken on line 6—6 of Fig. 2.

45 In the drawings, wherein for the purpose of illustration is shown a preferred embodiment of my invention, the numeral 10 designates my improved inner tube, as a whole, which may be formed of rubber, rubber coated fabric, or a rubber compound or other suitable material. The tube 10 is provided with preferably equidistantly spaced outwardly bulging convex portions 11, having concave portions 12 between their ends, as more clearly shown in Fig. 5. These alternately arranged convex and concave portions are preferably disposed in sets, extending in 55 the plane of rotation of the tube. As more clearly shown in Fig. 3, there are four of

these sets of convex and concave portions, while it is to be understood that the invention is in no sense restricted to this precise number, as the same may be decreased or increased as may be found advantageous. Arranged between the sets of convex outwardly bulging portions 11 are annular depressions 13, extending parallel therewith and in the plane of rotation of the inner tube. The annular depressions, as more clearly shown in Fig. 6, embody outwardly bulging convex portions 14, preferably equidistantly spaced with concave portions 15 alternately arranged with relation thereto. The convex 70 and concave portions 14 and 15 are transversely concave, as clearly illustrated in Figs. 3 and 4, and the concave portions 15 extend inwardly for a substantial greater distance.

75 It has been found that highly satisfactory results are obtained by having the convex portions or surfaces substantially equal to the concave portions or surfaces, while the invention is in no sense restricted to this specific arrangement.

80 The inner tube is provided with a valve 16 by means of which it may be inflated.

The numeral 16 designates a nonextensible outer shoe or casing to receive the inner tube, this shoe being secured to a rim 17, in the usual manner.

85 In the use of the inner tube, the same is arranged in the shoe 16 in the usual manner and before inflating this inner tube is ordinarily slightly smaller in all dimensions than the shoe. When the inner tube is inflated, by virtue of its construction, it expands in all directions, whereby its entire area is placed under compression, the inner tube being larger when expanded than the interior of 90 the shoe. It is thus apparent that if the inner tube is punctured, the material of the inner tube being under compression, the puncture is at once closed and the leak stopped.

95 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. A compression inner tube for a double 110 tube tire comprising a plurality of rows of alternate elevated and depressed portions,

said tube having portions between said rows extending below the said depressed portions.

2. A compression inner tube for a double tube tire comprising a plurality of rows of alternate convex and concave portions extending circumferentially of the tube, said tube having portions between said rows normally disposed below the circumferential plane of the said concave portions.

10 3. A compression inner tube for a double tube tire comprising a plurality of rows of alternate convex and concave portions extending circumferentially of the tube, said tube having separate alternate convex and 15 concave portions between said rows, the second named concave portions being normally disposed below the circumferential plane of the first named concave portions.

4. As a new article of manufacture, an inner tube for a pneumatic tire having initially produced therein an annular depression and said annular depression being provided with a plurality of supplemental de-

25 5. As a new article of manufacture, an inner tube for a pneumatic tire having initially produced therein an annular depression and said annular depression being provided with a plurality of supplemental de- 30 pressions, said supplemental depressions being equidistantly spaced and disposed entirely around the annular depression.

6. As a new article of manufacture, an inner tube for pneumatic tires having annular depressions initially produced in its 35 tread portion and side faces, the spaces be-

tween the depressions affording contacting surfaces, the contacting surfaces between the annular depressions in the tread and the annular depressions in the side faces being 40 provided with supplemental depressions.

7. As a new article of manufacture, an inner tube for pneumatic tires having annular depressions initially produced in its tread portion and side faces, the spaces between 45 the depressions affording contacting surfaces, the contacting surfaces between the annular depression in the tread and the annular depressions in the side faces being provided with supplemental depressions, said 50 depressions being disposed transversely of the contacting surfaces.

8. As a new article of manufacture, an inner tube for pneumatic tires having annular depressions initially produced in its 55 tread portion and side faces, the spaces between the depressions affording contacting surfaces, the contacting surfaces between the annular depression in the tread and the annular depressions in the side faces 60 being provided with supplemental depressions, the annular depressions being also provided with supplemental depressions in transverse alignment with the depressions 65 in the contacting surfaces.

In testimony whereof I affix my signature in presence of two witnesses.

NOBLE C. DOSS.
